UNITED STATES PATENT OFFICE.

WILLIAM B. HOWARD, OF DETROIT, MICHIGAN, ASSIGNOR TO SATTLEY COMPANY, OF DETROIT, MICHIGAN, A CORPORATION OF MICHIGAN.

COIN-WRAPPER CRIMPER.

Application filed January 29, 1923. Serial No. 615,620.

The invention relates to crimping apparatus for closing the ends of coin wrappers and consists in the novel features as hereinafter set forth.

5 To facilitate the handling of coin money it is the usual practice to place a predetermined number of coins of the same denomination in a paper package or wrapper ordinarily consisting of a tubular container sealed at one end and open at the other. The coins are inserted through the open end of the package which is afterwards sealed by folding over the edges of the wrapper, an operation ordinarily carried out by hand.

10 15 In order to eliminate this manual sealing of the coin holders I have provided a machine adapted to mechanically close the open end of the packages by crimping the edges of the wrapper thereby forming an effective seal which will not become unfastened and decreasing the time required for accomplishing this operation.

In the drawings:

Figure 1 is an elevation of a machine embodying my invention;

Figure 2 is a longitudinal section through the crimping mechanism;

Figure 3 is a plan view thereof.

A is a small electric motor provided with 30 a rotatable shaft B on which is mounted the crimping mechanism C. The latter comprises a cylindrical member D having an axial bore E for receiving the shaft B and provided with suitable securing means, such as the set screw F, threadedly engaging a radial bore G in the cylinder and projecting therethrough to engage the flat surface H of the shaft. An annular slot I extends axially of the member D forming a peripheral flange J, the inner surface of which is flared outwardly forming a cone shaped surface. Grooved rollers L are arranged within the slot I and journaled upon the radial pins M which are in threaded engagement with the member D.

In the operation of the device, the open end of the coin wrapper is guided by the cone shaped surface K into the annular slot I and is deflected inward by the grooved rollers L to form a return bend which effectively seals the package. The motor is mounted upon a suitable base and preferably is so arranged that the shaft B is inclined to the horizontal and the cylindrical member D has its cone surface extending

downward. As illustrated, the base N is provided with an inclined surface O to which the motor A is fastened by suitable securing means P. With this type of construction the filled coin wrappers may be inserted in the crimping machine while the coins are held in place by gravity and a large number of packages may be closed in a very short period of time.

The same crimping mechanism may be used for closing several different sizes of coin wrappers by making the inner diameter of the annular slot smaller than the smallest size coin wrapper and by having the cone shaped surface K of sufficiently large diameter to engage the open end of the largest wrapper used.

What I claim as my invention is:

1. The combination of an electric motor having a rotatable shaft, a base having an inclined face to which said motor is attached thereby inclining said shaft at an angle to the horizontal and crimping means for closing the end of a coin wrapper directly mounted upon the end of said shaft to rotate therewith, said crimping means being otherwise unsupported.

2. The combination of an electric motor having a rotatable shaft inclined at an angle to the horizontal, a member mounted upon the lower end of said shaft, said member being provided with an annular groove for receiving the edge of the coin wrapper, and means in said groove for deflecting said edge radially inward to form a sealing return bend.

3. A machine for closing coin wrappers comprising an electric motor having a rotatable shaft, a member secured to said shaft and provided with an annular groove extending axially thereof, and a series of grooved rollers journaled within said annular groove and having their axes extending radially of said member.

4. A machine for closing coin wrappers comprising a base, an electric motor mounted thereon with its axis inclined to said base, a member secured to said motor having an annular groove therein for receiving the edge of a coin wrapper, and means within said groove for deflecting said edge radially inward to form a sealing return bend.

5. A machine for closing coin wrappers comprising an electric motor having a rotatable shaft, a base for supporting said elec-

tric motor with the shaft inclined to the horizontal, a member secured to the lower end of said shaft, said member having a peripheral flange with a flaring outer edge, 5 a series of pins extending radially of said peripheral flange, and grooved rollers journaled upon said pins for deflecting the edge of the coin wrapper radially inward to form a sealing return bend.

10. 6. The combination of an electric motor having a rotatable shaft inclined at an angle to the horizontal, and crimping means for closing the end of a coin wrapper, directly mounted upon and solely supported by 15 the lower end portion of said shaft.

7. In a device of the character described, the combination with a member adapted to engage the edges of coin wrappers to crimp the same, of a base therefor, and an inclined 20 supporting face on the said base for supporting the said member with its axis inclined at an angle to the horizontal.

8. In a device of the character described,

the combination with a crimping mechanism, of means for driving the said crimping mechanism and a base for supporting the said driving means, the said base having a supporting portion arranged at an angle with respect to the horizontal whereby the axis of the said crimping mechanism is maintained at an angle with respect to the horizontal. 25 30

9. In combination, a member rotatable about an axis inclined at an angle to the horizontal, said member having a recess for receiving the edge of a coin wrapper, means for deflecting the edge radially inward to form a sealing return bend, and means for rotating said member. 35

10. In combination, an electric motor, a crimpler driven by said motor, and means for supporting said crimpler with its axis of rotation inclined to the horizontal. 40

In testimony whereof I affix my signature.

WILLIAM B. HOWARD.
